GEORGE M. LITTLE, OF PITTSBURGH, PENNSYLVANIA, ASSIGNOR TO WESTINGHOUSE ELECTRIC AND MANUFACTURING COMPANY, A CORPORATION OF PENNSYLVANIA.

METALLIC TERMINAL FOR ELECTRODES.

1,246,441.

Specification of Letters Patent. Patented Nov. 13, 1917.

Application filed August 11, 1913. Serial No. 784,031.

To all whom it may concern:

Be it known that I, GEORGE M. LITTLE, a citizen of the United States, and a resident of Pittsburgh, in the county of Allegheny and State of Pennsylvania, have invented a new and useful Improvement in Metallic Terminals for Electrodes, of which the following is a specification.

My invention relates to electrical connectors, and it has particular reference to contact terminals for electrodes which are employed in arc lamps. These terminals, when used in conjunction with electrodes insure the making of good electrical contact between the electrodes and conducting members which comprise the electrical circuits of the arc lamp.

As now constructed, electrodes are provided with a central conducting member or a metallic wire extending from end to end of the electrode. A metal cap, preferably of lead, is cast integrally upon the end of the wire which projects from the non-consumable end of the electrode. The metallic wire within the electrode decreases the resistance to the passage of current through the electrode. The metallic cap provides a metallic contact, and, consequently, good electrical connection between the electrode so equipped and the co-operatively engaged conducting members of the lamp circuit. When this electrode is consumed in the arc, it is replaced by a new electrode which is provided with an integrally cast metal cap similar to that above-mentioned. The expense of this replacement is an important item in the maintenance cost of an electric arc lamp.

One object of my invention is to provide a conducting terminal which may be used with a plurality of electrodes. It is necessary to furnish only one terminal for each arc lamp, thereby materially reducing the maintenance cost of the lamp.

Another object of my invention is to provide a metal terminal of the character indicated which will be durable, and the first cost of which will be low.

For a better understanding of the nature, the scope and the characteristic features of my invention, reference may be had to the following description and accompanying drawing forming a part hereof, in which Figure 1 is a side view, partially in section, of a portion of an arc lamp, an electrode

of which engages a device embodying a form of my invention; Fig. 2 is a sectional view of the electrode and a co-operatively engaged metal cap which are shown in Fig. 1; Fig. 3 is a view of the top of the metal cap; Fig. 4 is a side view of the metal cap; Fig. 5 is a view of the bottom of the cap; Figs. 6, 7, 8 and 9 show different views of a metal cap modified from the form which is shown in Fig. 2, the modification being 65 constructed in accordance with my invention, and Fig. 10 is a view, partially in section, of a modification of the arrangement shown in Fig. 1.

Referring to Fig. 1, a consumable electrode 1 of a metallic flaming arc lamp of a standard type of construction (a portion of the internal mechanism of the lamp being shown in the drawing) engages a metal cap 2 which embodies a form of my invention. The electrode is held in its operating position by a clutch 3 which is connected by a clutch rod 4 of an armature (not shown) of the feeding magnets of the lamp. Current, flowing through the electrode 1, 70 passes through the metal cap 2 which is embraced by a metallic sheath 5 constituting an extension of a metallic member 6. A flexible conductor 7, which is wound in the form of a helix and adapted to encircle 75 a guiding member 8 as the electrode 1 moves up or down, is electrically connected to the contact member 6 substantially as shown in the drawing. A tube 9 serves as a guide for the conductor 7, the electrode 1 and the 80 members co-operatively engaged therewith.

A metallic member or wire 10, centrally positioned within the electrode 1, extends from the consumable end of the electrode and projects from its upper end. The metal cap 2, being provided with a central opening 11, engages this projecting portion of the wire 10, thereby insuring a good electrical connection between the said electrode and the metal cap. As shown in Fig. 2, 85 the opening 11 comprises two different bores, the lower portion being a bore of a diameter smaller than that of the upper portion. Inasmuch as the diameter of the wire 10 approximates that of the bore at 90 the lower portion of the opening 11, the wire, after being inserted for a short distance in the opening 11, will tend to bind because of irregularities in its dimensions, if the bore is substantially uniform in di- 95

ameter, and thereby will prevent the forming of a satisfactory electrical contact between the cap 2 and the electrode 1. In order to preclude the wire from binding in the opening 11, the bore of the upper half of the opening has a diameter larger than that of the lower half of the said opening.

As the cap 2 is adapted for continuous use, the gripping portion of the opening 11 will wear as new electrodes are supplied to the lamp for replacing the consumed electrodes. Again, the projecting portion of the wire 10 is not always uniform in diameter in all the electrodes that may be supplied to the lamp. To insure against insufficient gripping action between the projection of the wire 10 and the cap 2, I have provided the cap 2 with a plurality of longitudinally extending saw-cuts, by means of which a spring or resilient action is obtained for yieldingly engaging the electrode and the cap.

As shown in the drawing, saw-cuts 12 are made in the upper portion of the cap 2 in close proximity to, and on each side of the opening 11, the said saw-cuts extending downwardly for about one-half of the total length of the cap 2. A diametral saw-cut 13, passing through the opening 11 of the cap 2, extends from the bottom of the cap to within a short distance of the top, in order to accentuate the spring action, as supplied by additional saw-cuts 14 that are positioned laterally to the opening 11 and extend from the bottom of the cap up to the point where the diameter of the bore of the opening 11 changes. The saw-cuts 14 may be made substantially at right angles to one another, as shown in Fig. 5, or, if a high degree of resilient action in the cap is not desirable, the said saw-cuts may be made as shown in Fig. 9. It will be understood that the positioning and the length of the above-mentioned saw-cuts may be varied considerably from those shown and described, the desirability of such cuts being to furnish a suitable spring action as the metal cap 2 grips the projecting portion of the wire 10.

When an electrode is withdrawn from the arc lamp, the cap 2, with the sheath 5, will be drawn downwardly and outwardly extending flare 15 formed around the lower periphery of the cap 2 prevents the cap from being drawn through an opening 16 in the clutch 3. At the same time, the cap 2 may be easily forced upwardly through the opening 16 by means of the contracting of the lower portion of the cap 2, which results from the saw cuts 13 and 14 being properly made. The flare 15 also assists in retaining the cap in the metallic sheath 5 because the flare effects a firm engagement between the cap and the sheath, the internal diameter of

the latter corresponding substantially to the external diameter of the upper portion of the cap. If the electrodes, as supplied by the manufacturer, have irregularities at their upper ends, it may be necessary to form an indentation 17 in the lower end of the cap 2, so as to bring the said cap and the engaging electrode into proper mechanical and electrical contact.

In Fig. 10, the metal cap 2 is shown as secured to the guiding member 8 by means of the threaded extension 18 which is formed upon the member 8. The projecting portion of the wire 10, extending into the central opening of the member 2, provides means for detachably engaging the electrode 1 and the metal cap 2. As previously explained, the saw cuts 13 and 14 and the different bores of the central opening 11 provide means whereby the projecting portion of the wire 10 may be yieldingly engaged by the cap 2 and may also be easily disengaged when replacing the burned electrode.

While I have herein described specific embodiments of my invention, it is not intended that the invention, in all its aspects, shall be limited to these particular embodiments, as it will be apparent to anyone skilled in the art that changes may be made within the scope of the appended claims.

I claim as my invention:

1. In an arc lamp, the combination with an electrode having an embedded central conducting core which projects from its upper end, of a metallic terminal therefor provided with a longitudinally extending opening having a plurality of different diameters and slits extending inwardly from each end thereof, thereby permitting said terminal to yieldingly engage said projecting portion of the core.

2. In an arc lamp, the combination with an electrode having an embedded metallic member which projects from its upper end, of a conducting terminal therefor provided with a longitudinally extending opening and slits extending inwardly from each end thereof, thereby imparting resilient action to said terminal so as to yieldingly engage said projecting portion of the embedded metallic member.

3. In an arc lamp, the combination with an upright electrode having an embedded conducting core which projects from its upper end, of a metallic terminal therefor provided with a succession of longitudinally extending openings of different diameters and slits extending inwardly from each end thereof, said terminal being so disposed that the smallest diameter opening is immediately adjacent to said electrode.

4. In an arc lamp, the combination with an electrode having an embedded core that extends beyond its upper end, of a terminal

therefor provided with a longitudinally extending opening which has a plurality of different diameters and saw-cuts which extend inwardly from one of the ends thereof and a flaring end for limiting the longitudinal movement of the said electrode.

In testimony whereof, I have hereunto

subscribed my name this 30th day of July, 1913.

GEORGE M. LITTLE.
